US0D1066307S

(12) **United States Design Patent** (10) **Patent No.:** **US D1,066,307 S**
(45) **Date of Patent:** **** Mar. 11, 2025**

(54) **MICROPHONE**

(71) Applicant: **Shure Acquisition Holdings, Inc.,**
Niles, IL (US)

(72) Inventors: **John Matthew Miller**, Grayslake, IL
(US); **Michael Alan Diamond**,
Arlington Heights, IL (US)

(73) Assignee: **Shure Acquisition Holdings, Inc.,**
Niles, IL (US)

(**) Term: **15 Years**

(21) Appl. No.: **29/852,821**

(22) Filed: **Sep. 9, 2022**

Related U.S. Application Data

(63) Continuation of application No. 29/750,255, filed on Sep. 11, 2020, now Pat. No. Des. 967,078, and a continuation of application No. 29/750,265, filed on Sep. 11, 2020, now Pat. No. Des. 967,079.

CLAIM

The ornamental design for a microphone, as shown and described.

DESCRIPTION

FIG. 1 is a top, front, right perspective view of a microphone showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

(Continued)

The uneven-length broken lines and the even-length broken lines immediately adjacent to the shaded area define the bounds of the claimed design and form no part thereof. The remaining even-length broken lines show portions of the microphone that form no part of the claimed design.

1 Claim, 7 Drawing Sheets
